UNITED STATES PATENT OFFICE.

JAMES B. LADD, OF ARDMORE, PENNSYLVANIA, ASSIGNOR TO UNITED STATES CAST IRON PIPE AND FOUNDRY COMPANY, OF BURLINGTON, NEW JERSEY, A CORPORATION OF NEW JERSEY.

CENTRIFUGAL CASTING-MACHINE.

1,347,582.

Specification of Letters Patent. Patented July 27, 1920.

Application filed November 1, 1918. Serial No. 260,657.

To all whom it may concern:

Be it known that I, JAMES B. LADD, a citizen of the United States of America, and resident of Ardmore, in the county of 5 Montgomery, in the State of Pennsylvania, have invented certain new and useful Improvements in Centrifugal Casting-Machines, of which the following is a true and exact description, reference being had to the 10 accompanying drawings, which form a part thereof.

My present invention relates to centrifugal casting machines, and was particularly devised for use in machines for casting iron 15 pipes of relatively large size, though the invention is not restricted to such use.

The general object of my invention is to provide an improved construction of the 20 rotary portion of such a machine and the bearings in which it is journaled.

The various features of novelty which characterize my invention are pointed out with particularity in the claims annexed to and forming a part of this specification. 25 For a better understanding of the invention, however, and the advantages possessed by it and specific objects obtained with its use, reference should be had to the accompanying drawings and descriptive matter 30 wherein I have illustrated and described preferred embodiments of my invention.

Of the drawings:

Figure 1 is a longitudinal vertical section through a pipe casting machine.

35 Fig. 2 is an end elevation of the machine.

Fig. 3 is a section on the line 3—3 of Fig. 1.

Fig. 4 is a section on the line 4—4 of Fig. 1.

40 Fig. 5 is a section taken similarly to Fig. 1, but on a larger scale and showing a portion only of the apparatus shown in Fig. 1.

Fig. 6 is a view taken similarly to Fig. 1 illustrating a modification, and

45 Fig. 7 is a view taken similarly to Fig. 6 of a portion of the machine differing slightly from that shown in Fig. 6.

In the drawings, and referring first to the construction shown in Figs. 1 to 5, inclusive, 50 A, A are spaced apart pedestals which form the supporting framework in which the rotating mold of the casting machine is journaled. The rotating mold comprises a mold body D proper, which, when the mold is in-

tended for forming bell end pipes, as in the 55 construction shown, may advantageously comprise a separable bell end section D' bolted to the body of the mold. The ends of the mold proper are bolted to heads or end members B and BA, which extend 60 through the pedestals A, A and are journaled therein. Preferably, as shown, the bearings for the end members B and BA are ball bearings. The ball bearing C for the end member B comprises an inner bearing 65 member C', which is preferably made separable from the end member B but shrunk on or otherwise secured to the latter, and is formed in its periphery with a circumferential groove forming the inner ball race for 70 the bearing balls C². The bearing also comprises an outer bearing member C³ received in the cylindrical seat A' of the corresponding pedestal A, and formed of two annular parts lying on opposite sides of the plane 75 passing through the ball centers. The outer bearing member is secured in the pedestal seat A' between an integral flange A² of the pedestal and a removable flange A³. The adjacent edges of the two halves of the outer bearing member are beveled off to provide a circumferential raceway for the roller balls. The division of the outer bearing member C³ into two halves, as described, permits of a 80 takeup adjustment to compensate for wear 85 and facilitates the assemblage and taking apart of the apparatus. The bearing CC between the mold and member BA of the corresponding pedestal differs from the bearing C only in that the inner bearing member 90 C¹⁰, shrunk or otherwise secured on the member BA, is formed with a cylindrical outer surface. With this arrangement the bearing C prevents axial displacement of the corresponding end of the rotating mold, 95 while the bearing CC permits the mold body to expand and contract in length as its temperature varies without any injurious consequence to the bearings. Each pedestal A is advantageously divided into separable upper and lower parts, as indicated at A⁴, to facilitate the removal of the mold from the pedestals. 100

The bell end of the mold is closed during the casting operation by an end member E, 105 which is seated in the end head B, and is detachably secured therein by means of the clamping bolts E'. As shown, the end mem-

ber E is formed with an axial bearing E² for the corresponding end of a mold charging trough, and with a surrounding tubular portion E³ projecting into the mold cavity 5 and forming a seat for the removable flange member E⁴ on which is mounted the frangible core E⁵, which forms a short inner wall portion of the mold cavity at the bell end of the mold. The opposite end of the 10 mold cavity is closed against the outflow of molten metal during the casting operation by an annular member F received in the mold body D, and preferably adjustably secured along the length of the latter as by 15 means of set screws to permit of the ready formation of cast pipes P of different lengths. The removal of the mold end member E at the end of the casting operation permits a pipe P, formed in the mold, to be 20 withdrawn from the mold through the corresponding end of the latter.

To avoid overheating of the mold I have provided means for water cooling it. The water cooling means shown in Figs. 1—5 25 comprises a stationary shell G surrounding the mold body and separated from the latter by a water space with an inlet connection G¹ for cooling water at one end, preferably the bell end, of the mold and an outlet G² for the cooling water at the other end 30 of the mold. The shell G is shown as divided along a diametrical plane into separable halves bolted together, and is supported at its ends upon brackets A⁵ 35 projecting from the inner sides of the pedestals A. To prevent leakage out of the water space at the ends of the shell G, suitable packings are provided between the ends of the shell G and the end 40 members B and BA. As shown, each packing comprises a resilient annular member H, formed of metal and rigidly secured at one edge to the end members B and BA, and having a sliding contact at its other edge 45 with the corresponding end of the shell G. This arrangement for sealing the joints between a rotating mold and a stationary water pocket surrounding the mold is not claimed herein, but is claimed in my co-pending application, Serial No. 260,656, filed 50 of even date herewith.

In the modified construction illustrated in Fig. 6 the mold DD proper is surrounded by a sleeve or mold housing BB, which integrally connects the rotatable bearing heads B¹⁰ and BB¹⁰. The latter from their integral connection, are, as shown, identical in their general construction and arrangement, and in the manner in which they are mounted 55 in the pedestals A, with the rotating heads B and BA, respectively, first described. As shown, the mold DD, which is enlarged at one end to form a bell ended pipe, is held in the rotatable housing BB 60 by the mold end member EE. When the

mold end member EE is removed, the mold DD with the pipe P cast therein, may be axially withdrawn from the casting machine. The tubular body portion of the housing member BB is separated from the mold between the ends of the latter by a cooling water space. The rotatable mold housing BB is provided with a stuffing box B²⁰ for the spigot end of the mold to prevent leakage out of the water space between the mold proper and the mold housing member BB. Surrounding the rotatable mold housing member BB is a stationary shell GA which may be formed and supported in substantially the same manner as is the shell G of 70 the construction first described, except that a rib G⁴ is preferably formed integrally of the shell GA to cause the cooling water entering the shell through the inlet G¹ to pass, for the most part, into the water space between the mold and the tubular body BB through the ports B², formed in the member BB. Ports B³ are formed in the member BB, adjacent the spigot end of the mold, to permit the water flowing along the mold 75 body DD proper to pass to the outlet G².

The apparatus shown in Fig. 7 differs from that shown in Fig. 6 essentially, only in that the housing body BC is bolted to the bearing heads of the mold housing instead of being integrally connected thereto, as shown in Fig. 6. In Fig. 7 also the cooling water passes between the external cooling water pipes and the space between the mold body proper and the shell BC through a passage 80 B⁶ formed in the corresponding rotating mold housing head and through ports B⁷ formed in a radial wall B⁸ at the side of the passage B⁶. Inner and outer flexible metallic gasket members H and HA, secured to 85 the outer stationary shell GB, and bearing against the wall B⁸, coöperate to form an annular water channel opening at one side through the ports B⁷ and at the other side to the corresponding circulating connection G².

The various forms of apparatus disclosed all possess the advantage of a simple and rugged mounting for the rotatable part of the casting machine. This mounting is one 90 reducing the frictional resistance to rotation to a practical minimum, and the anti-friction bearings provided are of a character to permit ready adjustments to compensate for wear, and the easy replacement of broken 95 and worn parts. The bearings moreover do not interfere with, and do not have their efficiency reduced by the thermal expansion and contraction in length of the mold. The formation of the mold body proper with a 100 removable bell end section, as illustrated in the construction shown in Figs. 1 to 5, reduce the initial cost of construction of such a mold, and permits of the formation of 105 pipes having differently shaped bell ends by 110

the substitution of different bell end sections of the mold. The provisions made for the ready removal of the mold proper from its rotatable housing, possible with the constructions shown in Figs. 6 and 7, possess important practical advantages under certain conditions of use. In particular, it facilitates the production of pipes of different shapes in the same casting machine, since it is a very simple and easy matter to replace one mold proper by another. Under some conditions also it is practically preferable to withdraw the mold proper, with the casting formed therein, and then extract the casting from the mold, rather than to draw the casting from the mold while the latter is mounted in the casting machine as is practically necessary with the constructions shown in Figs. 1 to 5. The construction shown in Fig. 7 has the special advantage over that shown in Fig. 6, that the rotatable mold housing may be less expensively and more advantageously cast in sections than in a single integral casting in some cases, and particularly in the case of machines for forming extra large pipe. Certain novel features of construction and arrangement pertaining to the water cooling of a rotatable mold end construction are claimed in my copending application Serial No. 260,656, filed of even date herewith.

While in accordance with the provisions of the statutes I have illustrated and described the best form of my invention now known to me, it will be apparent to those skilled in the art that changes may be made in the form of my invention without departing from its spirit, and that some features of my invention may sometimes be used to advantage without a corresponding use of other features.

Having now described my invention, what I claim as new and desire to secure by Letters Patent, is:

1. In a centrifugal casting machine the combination with a rotary mold and the supporting framework therefor, of ball bearings between said framework and the ends of the rotary mold, each of said bearings comprising inner and outer bearing members, the two bearing members of one bearing, and one bearing member of the other bearing, being formed each with a circumferential groove serving as a raceway for the bearing balls, and the fourth bearing member having a cylindrical ball engaging surface whereby bodily axial displacement of the mold relative to the framework is prevented while thermal expansion and contraction of the mold is permitted.

2. In a centrifugal casting machine the combination with a rotating mold and the supporting framework therefor, of a ball bearing between said framework and mold, comprising inner and outer bearing members and balls between said members, one of said members being divided transversely to the axis of rotation into two parts having adjacent corners beveled off to form a circumferential groove serving as a ballway and means for adjusting the distance between said parts to compensate for wear.

3. In a centrifugal casting machine the combination with a rotatable mold proper, of a rotatable housing in which the mold proper is removably inserted, said housing comprising end portions projecting beyond the ends of the mold proper and of greater diameter than the body of the housing, and a supporting framework in which said end portions of the mold housing are journaled.

4. In a centrifugal casting machine the combination with a rotatable mold proper, of a rotatable housing in which the mold proper is removably inserted, said housing comprising end portions projecting beyond the ends of the mold proper, a supporting framework in which said end portions of the housing are journaled, said housing and mold proper being spaced apart between the ends of the mold to provide a cooling water space, and cooling water circulating connections to said space.

5. In a centrifugal pipe casting machine, the combination with a rotatable mold body proper, of a rotatable housing in which said mold body is removably inserted, said housing comprising end portions projecting beyond the ends of the mold proper and a mold end member detachably secured to one of the end pieces of the housing and adapted to hold the mold body in place in the housing and to close the end of the mold cavity.

JAMES B. LADD.
